UNITED STATES PATENT OFFICE.

ARTHUR ERNEST JERRAM, OF LEICESTER, ENGLAND, ASSIGNOR TO UNITED SHOE MACHINERY COMPANY, OF PATERSON, NEW JERSEY, A CORPORATION OF NEW JERSEY.

SEWING-MACHINE.

1,120,201.

Specification of Letters Patent.

Patented Dec. 8, 1914.

Application filed August 4, 1909. Serial No. 511,216.

To all whom it may concern:

Be it known that I, ARTHUR E. JERRAM, a subject of the King of Great Britain, residing at Leicester, in the county of Leicester, England, have invented certain new and useful Improvements in Sewing-Machines; and I do hereby declare the following to be a full, clear, and exact description of the invention, such as will enable others skilled in the art to which it appertains to make and use the same.

This invention relates to improvements in sewing machines particularly of that kind which are adapted for sewing light harness with fine wax thread.

The invention comprises for a lock-stitch eyed-needle sewing-machine an arrangement of the thread take-up and the means for operating it that are so controlled by the thickness of the work as to cause the take-up to deliver thread only when the needle in penetrating arrives in a predetermined position in relation to that surface of the work which varies in its relation to the path of penetration of the needle. And operating means may be combined with this arrangement whereby the take-up is caused to draw from the supply an amount of thread that is proportional to the thickness of the work.

The take-up mechanism, according to this invention, may comprise a single slack thread take-up, a thread-measuring stop adjustable by the work to limit the movement of the take-up and a mechanism whereby the take-up is operated positively to set the stitch and yieldingly during the thread measuring part of its stroke. Also a thread-locking device may be included against which the stitch is set and which releases the thread for measuring and means may also be provided to cause the take-up before such release takes place to move slightly in a retrograde direction so as to slacken out the more or less elastic thread sufficiently to let it contract from a stretched to a normal condition.

A feature of the invention is that in a wax-thread lock-stitch sewing-machine the

arrangement of the thread-controlling devices is such that only two members, a thread locker and a single take-up, are in contact with the thread between the wax pot and the needle.

Conveniently, the mechanism for actuating the take-up may be a cam provided with a yielding section by which section the thread measuring part of the upstroke of the take-up is effected in a yielding manner.

The invention therefore comprises for a lock-stitch sewing machine, a take-up that is operated, first, positively to set a stitch against the resistance afforded by a thread-locking device and then yieldingly when the thread is released to draw a measured amount from the supply.

Other features of the invention comprise an improved device for measuring off an amount of thread that is proportional to the length of the stitch or to both the length of the stitch and the thickness of the work.

A preferred embodiment of the invention will now be described with the aid of the accompanying sheets of drawings but it is not to be considered that the invention is necessarily limited to the precise construction described or to the exact arrangement of the parts set forth as these are merely by way of example of a method of carrying the invention into effect.

In the accompanying drawings: Figure 1 is a front elevation of a sewing machine in which the features of the present invention are embodied in their preferred form; Fig. 2 is a plan of the machine, a portion of the casing being broken away to show underlying parts; Fig. 3 is a front elevation with portions of the casing broken away and with certain of the machine parts in section; Fig. 4 is an end elevation; Fig. 5 is a section taken substantially on the line 5—5 of Fig. 3; Fig. 6 is a view showing in detail and separate from the machine the needle bar, its operating means and the shuttle with its connected parts; Figs. 6^a and 6^b are views of the shuttle as seen in Fig. 6 but showing in each figure a different stage in the cycle of operation of the machine; Figs. 7 and 8

are views similar to Fig. 6 but with the parts in different operative positions; Figs. 9 and 10 show the shuttle in side elevation and in section but drawn to a scale larger than that of Figs. 1 to 8; Figs. 11 and 12 are detail views looking in opposite directions of a portion of the shuttle actuating mechanism. Fig. 13 is a view in end elevation of a portion of the machine drawn to a larger scale than Fig. 4. Fig. 14 is a detail view in end elevation of the cam disk from which the needle bar and take up are actuated. Fig. 15 is a vertical sectional view of the disk illustrated in Fig. 14. Fig. 16 is a view in side elevation, partly in section, of the mechanism illustrated in Fig. 14. Figs. 17, 18 and 19 are detail views illustrating the presser foot lifting mechanism, Fig. 17 being a plan view, Fig. 18 a view in end elevation and Fig. 19 a detail sectional view on the line 19-19, of Fig. 17, and Figs. 20, 21 and 22, are detail views of the thread locking mechanism, Fig. 20 being a view in end elevation, Fig. 21 a view in side elevation and Fig. 22 a section on the line 22-22, of Fig. 20.

Like reference letters indicate like parts throughout the drawings.

The general operation of the machine will first be described. A needle C (Fig. 4) and oscillating shuttle D are employed so as to produce a lock stitch. The movement of the needle C is such that, after the needle has penetrated the work and has been raised a sufficient distance to cause a loop of thread to be thrown out away from the needle between the needle eye and the work sufficient pause occurs in the vertical movement of the needle to give time for the shuttle to pass right through the loop of needle thread and simultaneously for the needle to move forward and feed the work. The loop of needle thread is engaged by a hook E and moved into the path of the shuttle beak D'. It should be noted that up to this point, *i.e.*, when the loop of needle thread is in readiness to be engaged by the shuttle beak D', approximately no thread under strain has been drawn through the needle. The shuttle beak then engages the loop and pulls thread through the eye of the needle in a direction substantially in the vertical plane containing the axis of the needle eye and preferably at an angle approximating to 45° with the line of penetration of the needle, as shown in Fig. 6^a, this angle having been determined experimentally to be the best. Sufficient thread is pulled down to pass the loop over the thread case D² of the shuttle D before the continued movement of the beak D' carries the thread into such an angle that it will slip from the beak of the shuttle and upward around the thread case D², the latter passing through the loop without pulling down

any further thread. The thread is then finally pulled up by the take-up to tighten the stitch. The frame A of the machine supports the main shaft B which is provided with a driving pulley B' and with a balance wheel B². The main shaft B carries two cam disks F and G (Fig. 3) for operating the various parts of the machine in a manner hereinafter to be described. The plate A' on which the work rests is curved so that its surface forms part of a cylinder with its axis running from side to side of the machine. A hole or slot is provided in this plate through which the needle C passes, and the shuttle D is arranged beneath the plate, as shown in Fig. 4. The needle is arranged with the axis of its eye extending in a direction parallel to that in which the work feeds, the position that is necessary for the production of the correct harness stitch. The needle C is mounted on a vertical needle bar C² that is connected by a link C⁴ to a pivot pin C⁶ projecting from a lever C⁸ that is pivoted at C¹⁰ in the cam disk G, see Figs. 6, 7 and 8. The lever C⁸ is pivoted at a point intermediate between the center and circumference of the cam-disk so that the pivot pin C⁶ may be moved toward or from the center about which the cam-disk G revolves. The cam disk is of substantially cylindrical form, hollowed out near its center on the side adjacent to the needle and closed on the other side and the lever C⁸ moves within the open part. The lever C⁸ is provided with an arm or tail C¹² projecting through a slot or opening in the cam G so that a runner C¹⁴ on the lever may engage a cam slot A²² in a fixed cam disk A². This cam slot is so shaped as to cause the pin C⁶ on the lever C⁸ to move in an irregular path (indicated approximately at X Fig. 7) and to pause for some considerable time adjacent to the axis of the main shaft B. This pause occurs after the needle C has penetrated the work and has been raised a sufficient distance to cause a loop to be thrown and continues while the shuttle D engages and passes through the loop of needle thread and also the pause gives time for the needle to move forward and feed the work.

The oscillating shuttle D (Figs. 9 and 10) is arranged approximately in the plane in which take place the several movements of the needle, and the shuttle comprises the thread-containing case or body D² pivoted at D³ to a carrier D⁴ that is substantially in the form of a thin disk or cylinder with its axis alined from side to side of the machine. Though in general form the carrier part of the shuttle is cylindrical a portion of sector like form is cut away to leave a space D⁵ wherein the adjacent edges D⁶ D⁷ of the carrier are concave and convex respectively, and so that the concavity forms

at the circumference of the carrier the beak D' adapted to engage the needle thread. The periphery of the carrier part of the shuttle is also cut away at D⁸ to provide 5 clearance for the hook E during its return movement to cast off and release the loop of needle thread when the shuttle is in the position illustrated in Figs. 7 and 8. The shuttle reel Z is carried on a spindle Z' 10 fixed in the cylinder casing or body D² and a catch Z³ controlled by a spring Z⁴ serves to retain the casing in its closed position. The thread delivers from the reel through a slot Z⁵ in the casing and passes under a tension device Z⁶ and through a slot Z⁷, and hole Z⁸ 15 in the casing to the work. The tension device is made of bent sheet metal and is pivoted at D⁹, an adjusting screw Z⁹ in the casing serving to regulate the pressure on the thread. The shuttle turns in a circular raceway A³ (Fig. 3) that forms a bearing for the carrier D⁴ and it is oscillated therein by a shuttle driver H (Fig. 4) that fits into the sector like space D⁵. Close to the hole Z⁸ and between the hole and the beak D' 20 of the shuttle, the bobbin case is provided with a rib Z⁹ over which the shuttle thread passes, the function of this rib being to prevent any slackness in the shuttle thread during the rotation of the shuttle. Beneath the plate A' over which the work is fed and preferably above the level of the shuttle the loop-taking hook E is arranged and by suitable mechanism to be hereinafter described, 25 is moved past the needle crosswise in a direction to it and to the direction of feed but inclined somewhat downward toward the shuttle axis as shown in Fig. 3. After the needle has risen about a quarter of an 30 inch from its lowermost position the loop that, by the rising of the needle, is thrown toward the back of the machine is engaged by the loop-taking hook E as seen in Fig. 6 and is deflected or driven in a direction 35 crosswise of the needle and of the line of feed into the path of the shuttle beak D'. The shuttle beak D' then engages the loop and pulls thread through the eye of the 40 needle in the direction which has been referred to above and as indicated in Fig. 6^a. Sufficient thread is pulled down to pass over the thread case D² before the continued 45 movement of the beak D' carries the thread into such an angle that it will slip inward 50 along the slight lump or projection D⁵* on the carrier below the beak; and simultaneously with this the forward end of the thread case D² engages the loop, expands it, 55 as seen in Fig. 6^b, and the thread case passes therethrough without pulling any 60 further thread through the needle eye. By the retrograde movement of the driver H sufficient clearance between it and the back 65 of the shuttle D is obtained to enable the loop of thread to be pulled up in the ordinary way to tighten the stitch, see Figs. 7 and 8.

To avoid any liability of the hook E engaging the shuttle thread a projection or bar E* is provided which prevents the shuttle 70 thread from being engaged by the hook E when the hook returns toward the shuttle. The shuttle is oscillated through somewhat over three quarters of a complete revolution by the driver H which comprises a piece 75 fitting into the sector-like space D⁵ in the carrier D⁴ of the shuttle. The driver H is carried upon an oscillating shaft H' (Fig. 3) which is arranged horizontally in alignment with the axis about which the shuttle 80 turns. This shaft at its right hand end is provided with an arm H², the outer end of which is provided with a slot to receive a block H²* (see Figs. 3 and 5). The block 85 H²* is pivotally connected to one end of a link H³ which is mounted to slide in a pivoted block H⁴. The block H⁴ is secured to a pivot pin H⁴* and the link H³ is provided with a longitudinal slot through which the pivot pin passes. The other end of the 90 link H³ is pivoted at H³* on a lever H⁵ fulcrumed at H⁶ to the frame of the machine and the upper end of the lever H⁵ is provided with a runner H⁷ in engagement with a cam groove H⁷* in the face of the cam 95 disk F. The shuttle driver H is provided with a needle-straightening device H¹⁰ (Fig. 4) consisting of an extension from the driver H. This extension H¹⁰ projects through the circular raceway of the shuttle 100 and upon the final portion of the retrograde movement of the shuttle driver H, engages the needle from behind and if the needle has been deflected toward the loop taking 105 hook E in penetrating the work, the device H¹⁰ will operate to push the needle up against the forward end of the slot in the plate A' into correct position for co-operation 110 with the loop-taking hook E.

The loop-taking hook E, the operation of which has been before described, is detachably fixed on the end of a sliding rod E' 115 (Fig. 3) that is supported in a bearing in the frame of the machine. The right hand end of the sliding rod is connected by a link E² to the lower arm of a lever E³ fulcrumed to the frame of the machine at E⁴. The upper end of this lever is provided with a spherical cam runner E⁵ that engages with a correspondingly-shaped cam-groove F* 120 formed in the periphery of the cam-disk F. The presser foot I (Fig. 4) for holding the work against the plate A' is attached to a vertical bar I' working in bearings in the machine frame A. The presser foot I is forced yieldingly against the work by a leaf spring I² (Figs. 3 and 4), which bears upon the upper end of the bar I'. The 125 presser foot is raised against the action of the spring I² to permit the work to be fed, 130

4
by a mechanism that comprises a collar I^3 loosely mounted upon the upper end of the bar I' , and a lever I^4 pivoted at I^5 on the collar and having a projection a which when the end b of the lever is lifted will first grip the bar I' against the collar, and then raise both collar and bar. The end b of the lever I^4 is raised at the proper time in each cycle of operation of the machine by a lever I^6 pivoted at I^7 upon the machine frame and provided with a roll I^8 that engages a peripheral cam surface on the cam disk G . When the roll I^8 is upon the low part of the cam the collar I^3 by the action of a spring plunger I^{11} is seated upon an abutment formed by a flange projecting from an adjustable rod I^{10} carried in the machine frame and at this time the position of the parts is such that the presser-foot bar I' is free to slide through the collar I^3 .

The material is fed by the movement of the needle C , which together with its needle bar C^2 is movable bodily sidewise for that purpose by mechanism about to be described. The needle bar C^2 is carried in a movable frame C^{15} mounted on a hollow rod C^{16} sliding in bearings in the machine frame A . The frame C^{15} is steadied by a guider comprising a plate A^4 (Figs. 1 and 4) attached to the frame of the machine, and having a slot in which the frame C^{15} fits. The slide rod C^{16} at its rear end is provided with a die C^{17} (Fig. 2) pivoted upon a pin J^2 that extends through a slot in the rod C^{16} and is secured to the end of a pendant arm J' of a rock shaft J that extends across the back of the machine and is mounted upon center points A^3 A^6 in the machine frame A . The other end of the rock-shaft J carries a curved arm J^3 connected to the feed-operating mechanism presently to be described and the rock-shaft has motion imparted to it therefrom which is variable according to the setting of that mechanism. To feed the work with precision notwithstanding the flexibility of the needle C , an assistant needle feeder is provided to engage the needle below the work-supporting or throat plate A' and to move in unison with the slide frame C^{15} . The assistant feeder comprises a plate K (Fig. 3) carried on a rocker K' that works about the shuttle shaft H' and has at its right hand end a projecting arm K^2 (Fig. 5) that is connected by a link K^3 to the curved arm J^3 which connects the rock-shaft J to the feed-operating mechanism. The effect of these connections is that the needle-carrying slide C^{15} and the needle C and the assistant needle feeder K are all moved backward or forward in unison.

The feed actuating mechanism comprises a cam groove in the left-hand face of the cam disk F with which groove engages a cam roller L carried by an extension of the

center pivot of a pair of toggle members L' L^2 . The extremity of the toggle member L^2 is pivoted to the curved arm J^3 . The extremity of the toggle member L' is forked and is pivoted by means of a pin L^8 to an adjustable member L^4 pivotally supported at A^7 in the frame A of the machine. The member L^4 is so pivoted that it can turn about an axis that is approximately coincident with the axis of the cam-roller L when the toggle L' L^2 is in the position in which the needle C is at the beginning of its work-feeding stroke. The member L^4 may be adjusted and clamped in any desired position by means of a screw L^5 passing through a slot A^8 in the casing of the machine frame and having a nut L^6 screwed upon it. By adjustment of the member L^4 , the position of the path of motion of the cam roller L can be altered so as to vary the feed movement by varying that component of the motion of the roller L which is available for moving the curved arm J^3 .

The thread take-up comprises a lever M pivoted at M' upon the machine frame A and provided with a runner or wheel M^2 over which the thread extends. The lever M is operated by a cam groove G^7 in the cam disk G with which engages a roller M^3 on an arm M^4 formed upon the hub of the take-up lever M . This lever is formed by a thin steel strip folded in two with the thread runner located inside adjacent to the fold. To warm the runner M^2 a plate M^5 is attached to the lever M behind the runner and this plate is heated by a burner N (Fig. 1) which directs a flame upon it. During the movement of the needle C from the point at which its eye is level with the work on penetrating to the time when the stitch is pulled in, the motion transmitted to the take-up lever M is positive and the thread is locked by a thread-locker presently to be described. After the thread has been pulled to set the stitch, however, a retrograde movement is imparted to the take-up sufficient to relieve the strain on the thread and then the thread is unlocked and the take-up is given a motion that varies according to the thickness of the work for the purpose of pulling sufficient thread through the thread-locker for the formation of the next stitch. To permit of this variable motion of the take-up lever M the cam disk G is provided with a yielding section G' of which one side forms a portion of the outer wall of the cam-groove G^7 .

The section G' is pivoted at G^2 to the cam disk G and a spring G^3 attached respectively to the section and to the cam disk tends to maintain the section against a stop G^4 , in which position of the section the outer wall of the cam groove G^7 is continuous. The normal shape of this cam-groove is such that if the yielding section G' does not operate (that is to say if it is not moved away from

the stop G^4) sufficient thread would be pulled off after each stitch has been pulled in, and the thread locker released, to provide for stitching the thickest material. To provide for the smaller amounts of thread required for thinner work, there is a stop-piece M^6 on the hub of the thread take-up lever M and this stop-piece is adapted to be intercepted by a stop I^{12} which changes its position in unison with variations in the thickness of the material. The stop I^{12} is preferably arranged on an arm I^{13} fixed on the presser-bar I' .

In operation on thinner material, after the stitch is pulled in and the thread has been unlocked the yielding section G' of the cam G will yieldingly impel the take-up M to pull the thread through the thread locker until the stop piece M^6 is intercepted by the stop I^{12} whereupon the yielding section of the cam, by the continued rotation of the main shaft B , will be deflected from its normal position. Upon further rotation of the cam, some portion of the inner wall of the cam groove will be brought into engagement with the cam-runner M^3 and will cause the thread take-up M to be depressed and the timing of the parts is such that this will occur exactly at the time the eye of the needle reaches the level of the material, notwithstanding variations in the said level; it being understood that the distance the needle has to travel before its eye reaches the said position and the pause before the end of the upstroke and beginning of the downstroke of the take-up are both controlled by the thickness of the work.

The thread locker comprises a roller O (Fig. 1) which is moved to and from a fixed abutment O' consisting of a piece screwed to the frame of the machine and curved at its top end so that the roller O clamps the thread between the two. The roller is carried on a pin O^2 eccentrically mounted on a small rock-shaft O^3 working in bearings in the frame of the machine. Attached to the rock-shaft O^3 is an arm O^4 that rests on a spring-pressed plunger O^5 which latter normally moves the rock-shaft O^3 to cause the thread-runner O to clamp the thread against the abutment O' . Another arm O^6 (Fig. 3) working about the rock-shaft O^3 is actuated through a roller O^7 upon it by a cam formed on the periphery of the cam-disk G . The arm O^6 has a "lost motion" connection with the rock-shaft O^3 whereby it operates to move the roller O away from the abutment O' to release the thread at the times required. A spring is employed to maintain the roller O^7 constantly in contact with the cam, and the lost motion connection is for the purpose of enabling at the same time various thicknesses of the thread to be gripped.

The machine is provided with a stitch length measurer which comprises a tubular

slider P (Fig. 4) with a projecting toe P' adapted at times to engage the thread just behind the needle C so as to tuck it in close to the surface of the material adjacent to the position of the next needle hole. This occurs 70 while the needle is out of the work as shown in Fig. 4. The tubular slider P is mounted on a vertical guide rod P^2 secured to the needle bar carrying frame C^{15} and it moves to and fro in unison with the needle while the work 75 is being fed and while the needle is returning. The tubular slider P is controlled as to its vertical position by an inclined guide rod P^3 fixed to the presser bar I' and working in a hole in the slider; and by this arrangement the slider P is lifted away from the work as the feed takes place and lowered toward the work as the needle is returned by its carrier C^{15} into its work-penetrating position. The attachment of the slider P to 80 the presser foot I also insures that the toe P' shall be moved close on to the surface of work of varying thicknesses when it tucks in the thread. In operation, after the work is fed and the stitch has been pulled in, 85 the return feed motion of the needle will bring about a corresponding return of the stitch length measurer, bringing it into contact with the thread so as to tuck in the thread close to the surface of the material 90 just behind the position of the next needle hole. The work-feeding motion will then move to toe rearwardly and upward so as to leave the thread unobstructed for the pulling in of the stitch. It will be noted 95 that the stitch length measurer P' operating in conjunction with the take-up M insures that sufficient thread to form a stitch shall be pulled through the thread locker O O' notwithstanding variation in the length of 100 the stitch or of the thickness of the work.

With the before described improved arrangement of devices it should be noted that the number of surfaces with which the needle thread contacts in its passage from 110 the supply to the work is reduced to a minimum and merely comprises the roller O of the thread locking device O O' , the roller M^2 of the take-up lever M and the eye of the needle C ; additionally, in passing this 115 thread around the shuttle D a minimum of friction is engendered in the eye of the needle and the loop passes over the shuttle without strain so that the result of the whole combination is the production of much better waxed thread sewing than has been possible heretofore in the eyed needle type of machine.

The nature and scope of the present invention having been indicated and a machine embodying the several features thereof in their preferred form having been specifically described, what is claimed is:

1. A lock stitch sewing machine, having, in combination, stitch forming devices in- 130

- 6 cluding an eyed needle, a take up, means for positively actuating the take up to set the stitch and to deliver thread to the needle while the needle is penetrating the work, 5 and means controlled by the thickness of the work for starting the thread delivering stroke of the take up at the time when the eye of the needle reaches the level of the work, notwithstanding variations in said 10 level.
2. A lock stitch sewing machine, having, in combination, stitch forming devices including an eyed needle, a take up, mechanism for positively actuating the take up 15 to deliver thread to the needle while penetrating the work and for positively actuating the take up to set the stitch and then yieldingly to draw thread from the supply, and means controlled by the thickness of 20 the work for limiting the thread drawing stroke of the take up and for starting the thread delivering stroke when the needle arrives at a predetermined position with relation to the surface of the work.
- 25 3. A lock stitch sewing machine, having, in combination, stitch forming devices including a needle, a take up, a thread measuring stop adjustable by the work to limit the movement of the take up, and mechanism 30 for actuating the take up positively to set the stitch and then yieldingly to draw thread from the supply.
4. A lock stitch sewing machine, having, in combination, stitch forming devices including a needle, a take up, a thread locking device against which the stitch is set, means for actuating the take up positively to set the stitch and then yieldingly to draw thread from the supply, means for actuating 40 the thread locking device to unlock the thread after the stitch is set, and means controlled by the thickness of the work for limiting the thread measuring stroke of the take up.
- 45 5. A lock stitch sewing machine, having, in combination, stitch forming devices including a needle, a take up, a thread locking device against which the stitch is set, mechanism for actuating the take up to set the 50 stitch and then draw thread from the supply, having provision for imparting a retrograde movement to the take up after the stitch is set to relieve the strain on the thread, and means for actuating the thread locking device to release the thread after 55 the retrograde movement of the take up.
6. A lock stitch sewing machine having, in combination, stitch forming devices including a needle, a take up, means for actuating the take up, first positively to set the 60 stitch and then yieldingly to draw thread from the supply, and means controlled by the thickness of the work for limiting the thread drawing stroke of the take up.
7. A lock stitch sewing machine having, 65 in combination, stitch forming devices including a needle, a take up, a cam provided with a yielding section for actuating the take up first positively to set the stitch and then yieldingly to draw thread from 70 the supply, and means controlled by the thickness of the work for limiting the thread drawing stroke of the take up.
8. A lock stitch sewing machine having, 75 in combination, stitch forming devices including a needle, a take up, means for actuating the take up first positively to set the stitch and then yieldingly to draw thread from the supply, a presser foot, and a stop connected to the presser foot for limiting the thread drawing stroke of the take up.
9. A lock stitch sewing machine having, 80 in combination, stitch forming devices including a needle and a shuttle, means having provision for adjustment for feeding the work, a thread lock and means operating automatically during each cycle of operations of the machine to draw from the supply through the thread lock an amount 85 of thread proportional both to the length of stitch and to the thickness of the work.
10. A lock stitch sewing machine having, 90 in combination, stitch forming devices including a needle and a shuttle, a thread lock, a thread measuring device, means for actuating said device to draw thread from the supply through the thread lock, means controlled by the thickness of the work for 95 limiting the thread drawing stroke of said 100 device, a second thread measuring device, and means for actuating said second device to draw an amount of thread from the supply through the thread lock proportional to the length of the stitch.
11. A lock stitch sewing machine having, 105 in combination, stitch forming devices including an eyed needle, a thread measuring device arranged to engage the thread between the eye of the needle and the work 110 while the needle is out of the work, and means for actuating said device to measure an amount of thread proportional to the length of the stitch.
12. A lock stitch sewing machine having, 115 in combination, stitch forming devices including an eyed needle, a thread measuring device arranged to engage the thread between the eye of the needle and the work, means for moving said device back and 120 forth in the line of feed a distance equal to the length of the stitch, a presser foot, and a connection between the presser foot and the thread measuring device to determine 125 the position of the device with relation to the surface of the work.
13. A lock stitch sewing machine having, 130 in combination, stitch forming devices in-

cluding an eyed needle, a feed frame, a thread measuring device mounted on the feed frame arranged to engage the thread between the eye of the needle and the work, a presser foot, an inclined guide on the presser foot engaging the thread measuring device and arranged to move said device

toward and from the work during the backward and forward movements of the feed frame.
